UNITED STATES PATENT OFFICE.

EMANUEL HEIMANN, OF BRUNSWICK, GERMANY.

EXTRACTING APPARATUS.

SPECIFICATION forming part of Letters Patent No. 733,200, dated July 7, 1903.

Application filed September 20, 1902. Serial No. 124,223. (No model.)

To all whom it may concern:

Be it known that I, EMANUEL HEIMANN, engineer, a subject of the King of Prussia, Emperor of Germany, residing at Brunswick, 5 Duchy of Brunswick, Germany, have invented certain new and useful Improvements in Extracting Apparatus, of which the following is a specification.

This invention relates to extracting apparatus.

The object of the invention is the provision of an apparatus including means for extracting the prime constituents of the material under treatment by employing a solvent, 15 means for withdrawing the solvent from the receptacle containing the material under treatment, means for distilling or evaporating said solvent, means for surrounding the receptacle or receptacles containing the material 20 under treatment with the fumes or vapors of said distilled or evaporated solvent, means for passing said fumes or vapors through a condenser to reduce them to liquid condition, and means for again supplying said solvent in liquid condition to the receptacle containing the material under treatment.

Referring to the accompanying drawings, forming a part of this specification, Figure 1 represents in elevation an apparatus constructed according to my invention; and Fig. 30 2 is a plan view of the receptacles containing the material under treatment, the casing surrounding said receptacles, and the pipes communicating with said casing and receptacles.

The apparatus, briefly described, comprises a casing, a plurality of extracting-receptacles in said casing, a siphon leading from each of said receptacles and communicating with a distiller or evaporator, a pipe leading from 35 said distiller or evaporator and communicating with the said casing, a pipe leading from said casing and communicating with a condenser, and a pipe leading from said condenser and communicating with each of the 40 receptacles in said casing.

The reference character A indicates the extracting apparatus proper, B the distiller or evaporator, and C the condenser.

Referring to Fig. 1, the reference character 50 a indicates the casing of the extracting apparatus. Within this casing is disposed a plurality of receptacles b (shown in dotted lines)

for containing the material under treatment. Each of the receptacles b is provided at its top with a hinged door c and at its bottom 55 with a hinged door i, each of the doors i being provided with a counterweight, as shown.

Leading from an outwardly-extending portion or chamber i' at the lower end of each receptacle b is a siphon e, which is disposed 60 on the outside of the casing a and empties into a pipe k, communicating with the distiller or evaporator B. A delivery-pipe f extends from the upper end of the distiller or evaporator B to the casing a and delivers 65 vapors or fumes generated in said distiller or evaporator to the casing a, which vapors or fumes surround the receptacles b in said casing.

Leading from the upper end of the casing 70 a is a pipe g, which communicates with the condenser C. A plurality of branch pipes g' connect the receptacles b at their upper ends with the pipe g, as shown in Fig. 2.

Leading from the condenser C and communicating with each of the receptacles b in the casing a through branch pipes h' is a pipe h.

It will be understood, of course, that any preferred form of distiller or evaporator B and condenser C may be employed, and as 80 the particular construction of these devices forms no part of my present invention I have only illustrated them conventionally.

Constructed as above described the operation of my improved apparatus is as follows: 85 A quantity of the material which is to be treated is placed in one of the receptacles b by means of its hinged door c. Any preferred character of liquid solvent is then fed to said receptacle b and permitted to extract 90 or dissolve out the prime constituents of the material under treatment. When the solvent in the receptacle b reaches a level equal to the highest point of the siphon e, which leads from the particular receptacle b being 95 used, said solvent overflows through said siphon into the pipe k and is conducted thereby into the evaporator or distiller B, where it is converted into vapor or fume and conducted by the pipe f to the casing a. Within 100 the casing a the hot fumes or vapors from the distiller or evaporator B surround the receptacle or receptacles b in said casing and materially aid in heating said receptacles,

whereby the action of the solvent upon the material being treated is facilitated. From the casing *a* the fumes or vapors of the distilled or evaporated solvent are conducted to 5 the condenser *C* by the pipe *g*. In the condenser *C* the evaporated solvent is once more reduced to liquid condition and flows through the pipe *h* to the particular receptacle *b* containing the material under treatment. Said 10 solvent then overflows again through the siphon *e*, and the operation continues, as before, in a cycle.

When the constituents of the material under treatment in one of the receptacles *b* are 15 nearly all extracted by the solvent with which said material has been treated, a pressing or squeezing action is exerted upon said material in any desired manner to express therefrom any of the solvent which may remain 20 therein. This pressing or squeezing of the material in the receptacle *b* forces all the solvent contained therein to pass through the siphon *e* into the delivery-pipe *k* of the distiller or evaporator. The squeezed or 25 pressed material in the casing *a* may be permitted to remain therein a sufficient length of time to be dried by heat generated within the casing *a* around the receptacles *b* by the fumes or vapors delivered from the evaporator 30 *B*. When completely dried, the material in the receptacle *b* is removed therefrom through the lower counterbalanced door *i*.

During the extracting operation any vapor which may be generated in the receptacle *b* 35 through the evaporation of the solvent contained in said receptacle by the heat of the apparatus is conducted through the branch pipe *g'*, leading from said receptacle, into the main pipe *g*, and from said main pipe is delivered 40 to the condenser *C*, wherein it is condensed, being afterward conducted by the pipe *h* back to the receptacle *b*. By means of this construction it will be seen that no loss of solvent through evaporation is possible. 45

In working my improved apparatus it will be understood that one of the receptacles *b* is first placed in operation, and after the extracting operation therein has been about 50 one-fourth completed a second receptacle *b* is placed in operation, as described with respect to the first receptacle. When the extracting operation in the second receptacle has been about one-fourth completed, a third 55 receptacle is placed in operation, and so on. It will be understood, of course, that this method of working is adapted for the apparatus when four receptacles *b* are employed, as shown; but it will be understood that any 60 desired number of receptacles *b* may be employed without departing from the spirit of my invention, and the method of working will of course be made to correspond with the number of receptacles employed.

65 The receptacles *b* are placed in operation one after the other in regular order for the purpose of preventing the apparatus from

becoming cooled during the removal of the completely-treated material from the receptacles *b*. If all of the receptacles *b* were discharged and refilled at the same time, the apparatus would have an opportunity to become cool and much inherent heat would thus be lost. 70

From the foregoing description it will be 75 seen that the operation of my extracting apparatus is practically continuous and that by its employment I am enabled to thoroughly extract all the valuable or prime constituents 80 of the material under treatment without loss of time or heat.

It will be understood that the receptacles *b* may be heated in any desired manner—such, for instance, as by employing steam-coils or the like. As such methods of heating receptacles, however, are old and well-known in the art, and as they form no part of my present invention, I have not deemed it necessary to illustrate them in the drawings. 85

If desired, I may dispense with the distiller 90 or evaporator *B*, and by elevating the lower end of the receptacle *b* above the bottom of the casing *a* and applying heat to the bottom of said casing convert said casing into a condenser, which will in all essential respects 95 perform the function of the distiller or evaporator *B*. It will be understood that the receptacles *b* are elevated above the bottom of the casing *a* in order that the siphons *e* may discharge the solvent contents of said receptacles *b* into the lower portion of the casing *a*, wherein they are converted into fume or vapor and surround said receptacles *b*, thus effectually heating the receptacles and aiding the extracting operation. 100

Having thus described my invention, what I claim as new, and desire to secure by Letters Patent, is—

1. An extracting apparatus comprising a jacket-casing; a receptacle therein, the upper end of which is closed normally; an evaporator; and a condenser; said receptacle communicating with said evaporator; said evaporator with said casing; said casing with said condenser; and said condenser with said receptacle. 110

2. An extracting apparatus comprising a jacket-casing; a receptacle therein; doors on the upper and lower ends of said receptacle; an evaporator; and a condenser; said receptacle communicating with said evaporator; said evaporator with said casing; said casing with said condenser; and said condenser with said receptacle. 120

3. An extracting apparatus comprising a jacket-casing; a receptacle therein; doors on the upper and lower ends of said receptacle; an evaporator; and a condenser; said receptacle communicating at its upper end with said condenser, and between its upper and lower ends with said evaporator; said evaporator communicating with said casing; said casing with said condenser; and said condenser with said receptacle by a passage in 125 130

dependent of the first-named communication between said receptacle and said condenser.

4. An extracting apparatus comprising a jacket-casing; a plurality of receptacles in said casing; doors on the upper and lower ends of each said receptacles; an evaporator; a condenser; a siphon connecting each of said receptacles with said evaporator; a communication between said evaporator and said casing; a communication between said casing and said condenser; a communication between said condenser and each of said receptacles; and a second communication between

said condenser and each of said receptacles; said communications being independent of each other and one terminating in each of said receptacles in a lower plane than the other.

In testimony whereof I have hereunto set my hand in presence of two subscribing witnesses.

EMANUEL HEIMANN.
